SIGNAL CHIME

Lowell M. Alexander, Cincinnati, Ohio, assignor
to Nu Tone Chimes Inc., New York, N. Y., a
corporation of New York

Application January 8, 1940, Serial No. 312,869

3 Claims. (Cl. 200—122)

This invention relates to electrically operated chimes and signals adapted for use in homes or offices in place of the usual bells or buzzers. More specifically, however, the invention is directed to chimes which are capable of sounding a plurality of notes or signals when once energized, as through the depression of a push button switch.

Chimes of low cost heretofore have been capable of sounding one or, at the most, two successive signals without repeated actuation of the main switch. In the usual devices, solenoid strikers are employed for vibrating reeds or bars, or tubes placed adjacent resonators for amplifying the sound. In some cases, the solenoids are arranged to operate between reeds, the strikers of the solenoid being impelled first in the direction of the one reed and then rebounding under the influence of a spring to strike the other reed to sound a second note. In many instances the sound from the chimes of this type fail to attract the attention desired and the signals are unnoticed.

In some of the more expensive chime devices motor driven rotary switches have been used, both for repeat signaling and for sounding a succession of notes of different tone. However, the construction of these chimes is quite complex; motor are requisite, special transformers are required in most instances and the chimes, on the whole, have been much too costly to meet the public demand.

The present invention provides chimes which are capable of repeatedly sounding signals at periodic intervals when they are energized through a push button. For instance, four, five, eight or ten notes may be sounded at intervals of fractions of a second. The number of notes and the length of time elapsing between successive notes may be varied to suit the conditions desirable in the particular use of the chimes.

A primary objective of the present invention has been to provide a simple but rugged apparatus which can be constructed at low cost and which is capable of sounding automatically a succession of signals in response to primary manual control through a push button.

A further object has been to provide a chime device embodying an automatic controller for repeat signaling which is sufficiently compact to be incorporated with the sound-producing apparatus, in order that the entire assembly may be housed in a small dust cover and be of attractive appearance.

5 A further object has been to provide a chime signal capable of operating from the usual low voltage transformer of, for instance, six, eight or fourteen volts, and capable of being installed readily in homes and offices by connection to the wire outlets arranged to supply the usual bells or buzzers.

10 A still further object has been to provide at low cost, chime apparatus which is capable of sounding signals automatically at periodic intervals when energized initially by the momentary depression of a push button.

15 Briefly, the chimes of the present invention are energized repetitively in response to a primary manual control through a push button or the like, through automatically operating thermo-responsive control elements. These preferably are bimetallic strips which are arranged to co-operate with one another and move or warp in 20 the same direction when heated.

25 For a chime to operate satisfactorily it must respond promptly when a push button of the type conventionally used is operated. If a single bimetallic element equipped with a heater is used to cooperate with a stationary contact several difficulties are encountered in obtaining proper operation of the signals. The intensity of heat provided by the heater determines the rapidity with which the bimetallic element responds to the operation of a push button. If the heater is adjusted so that it heats the bimetallic element quickly to obtain prompt response, then it is impossible to obtain the desired interval of time between the succession of 30 signals, and a hammering or chattering effect is produced. On the other hand, if the size of the heater is reduced so as to obtain the desired time interval between signals, then there is a long period, for instance, four to six seconds, 35 elapsing before the first signal note is sounded after the push button is operated.

40 The problem has been to obtain a signal which responds promptly to the operation of a push button and which also thereafter continues to sound a succession of notes at spaced time intervals so long as the push button continues to be depressed. This desirable result is obtained by using cooperating bimetallic strips each having a heating element, with the heating elements 45 being so adjusted in relation to the bimetallic strips which they influence and in relation to each other that circuit making contact is established promptly upon the operation of a push button, so that there is an immediate signal response and that signals are sounded at spaced 50

intervals of time thereafter to produce a relatively slow measured beat.

The solenoid striker or other electrically operated sounding unit for operating the chime is interconnected with the resistance heater elements, but the resistance of the entire circuit is such that with a given electrical supply, the current permitted to flow in the circuit is insufficient to operate the sounding unit when all resistances are in circuit, but is sufficient to operate the sounding unit when the resistance of the circuit is of lesser magnitude.

The thermoresponsive elements operate to control the amount of resistance in the circuit, periodically shunting a portion of it so as to permit to flow a current of sufficient magnitude to operate the sounding unit.

In the preferred structure the bimetallic strips operate contacts which, when in engagement, shunt or short circuit one of the heating coils. It is recommended that this latter heater be of relatively high resistance, in comparison with the other, in order that the device respond promptly when the push button is depressed. The contacts normally may be either spaced apart or be in engagement with one another, as desired. In the following specification they are shown and described as being spaced apart when they are in repose. Since the thermoresponsive elements move in the same direction they are self-compensating in respect to changes in ambient temperature.

In but a second or a fraction after the current flows in the circuit, the high resistance heater warps its bimetallic element more than the adjacent one so that the contacts are closed, shunting the high resistance, the current increases to magnitude sufficient to operate the sounding unit and a note is struck. At the same time the current now flowing through the heater on the other element heats it and causes it to move away from the first and break the contact. This operation restores the first resistance in circuit and it in turn heats the first element to cause it to move toward the other and reestablish contact for repetition of the cycle.

Thus, the contact on the first bimetallic element moves toward the second, and the second then moves away from the first. Or otherwise expressed, the one contact is driven to "chase" the other which recedes from it after momentary engagement. At each engagement a note is struck. These relative "chasing" operations continue, according to one arrangement of the invention, so long as the push button is depressed, with notes being sounded at intervals of fractions of seconds more or less depending upon the electrical conditions and the spacing of the contacts. It is to be noted that neither of the resistances by which the bimetallic elements are warped is heated or energized continuously, and it is also to be noted that when the heaters are not energized they are cooling and therefore receding. It is for this reason that the chasing of one bimetallic element by the other takes place in a limited range of distance. According to another arrangement of the invention, the push button is provided with a contact holding device which is released through the warpage of a thermoresponsive element. In the latter modification the chime operates automatically for a predetermined period, once the button is depressed. The term "chasing," as used in the specification, is applied, not literally, but to describe the relative operation of the elements,

one moving toward the other when it is heated and the second moving away from the first when it is heated, the first thus relatively chasing the second.

5 In some instances it is desirable to have chime signals controlled from several different points, for instance, from a front door and from a back door. In accordance with the present construction, an individual solenoid striker is provided to respond to individual switches located at the various points of control. The switches are connected in parallel so that one or a plurality of strikers likewise connected may be controlled from but a single thermocontroller unit. This 10 feature is, of course, very important from a cost standpoint.

These principles upon which the invention is predicated may be utilized in various modes of construction. A preferred embodiment of the 20 invention and several illustrative modifications are shown in the accompanying drawings and those skilled in the art readily will comprehend the other modifications to which the invention is susceptible.

25 In the drawings:

Figure 1 is a diagrammatic illustration of the typical circuit of a chime adapted to be operated from two points of control such as a front door and a rear door.

30 Figure 2 is an illustration showing the striker mechanism for a tubular or gong type chime which may be used in place of the resonator sounder of Figure 1.

35 Figure 3 is a modification of the circuit shown in Figure 1.

Figure 4 is a further modification of the circuit shown in Figure 1.

Figures 5 and 6 are diagrams illustrating the operation of the circuit of Figure 4.

30 Figure 7 is an illustration of a push button arranged to hold the primary circuit for automatic operation of a chime.

Figure 8 is an illustration of a modified thermocontroller unit.

45 In Figure 1, the chime sounding mechanism is illustrated generally at 1 and comprises electrically operated striker units 2, a resonator 3, and a reed or chime bar 4 placed adjacent the resonator. Each of the striker units comprises an armature 5 which is adapted to be moved magnetically when its surrounding solenoid coil is energized electrically. One of the strikers may be arranged to strike one bar then rebound to strike the other, for sounding double notes, if desirable. The details of the construction of these elements form no part of the invention, are well known in the art and further description of them is not believed necessary.

50 The thermocontroller unit is indicated generally at 6 and comprises bimetallic element 7 and a bimetallic element 8 placed adjacent one another and both preferably mounted upon an insulator block (not shown). It is contemplated that the thermocontroller unit and the sounding assembly 1 be mounted upon a base plate and housed within an appropriate dust cover, although if desirable the thermocontroller can be installed independently of the sounding mechanism. The thermocontroller may be of very small size, so that the space it occupies is inconsequential.

55 Bimetallic elements 7 and 8 carry cooperating contacts 9 and 10. These contacts normally are spaced apart but are sufficiently close together 60 so that they may engage one another upon warp-

age of one of the elements. The spacing of the contacts governs, to an appreciable degree, the promptness of response of the apparatus. In most instances satisfactory results are obtained if they are spaced apart about .001 inch, when in repose.

The strip 7 carries, preferably wound about it, a resistance coil 11. In the remainder of the specification this coil is termed the low resistance heater. The strip 8 carries wound about it in similar fashion a resistance element 12 which, in the remainder of the specification, is termed the high resistance heater. Nichrome wire preferably is utilized in forming these resistances, the wire being appropriately enameled so as to insulate it from the metallic strip on which it is carried.

A transformer 13 is employed to provide energy to the apparatus. This transformer is intended to deliver approximately 12 to 14 volts when operated from the distribution circuit of 110 volts or thereabouts. Transformers of this size are usually installed in the homes; therefore, from the manufacturing point of view, the apparatus need only be provided with terminals 14 and 15 for connection of the device with terminals from the transformer.

Two respective terminals of the solenoids 2 are connected together through the leads 16 and 17 to the lead 18 taken from the terminal 14. The leads 16 and 17 include push button switches 19 and 20. These may correspond respectively to the front door and rear door push buttons in a home.

The two other respective terminals of the solenoids 2 are connected together through leads 21 and 22, to a connector 23 which is fastened electrically to the bimetallic strip 8 of the thermocontroller. One of the ends of the high resistance heater 12 is also fastened electrically to the bimetallic strip 8 and the other end is likewise fastened to the bimetallic strip 7. A terminal of the low resistance heater 11 is fastened to the bimetallic strip 7 and the other end of this resistance heater is connected, through lead 24, to the other terminal 15 of the apparatus. If desirable, the terminal of high resistance coil may be connected to lead 24 instead of to the bimetallic strip 7. Likewise, if desirable, only one electrostriker unit need be employed in place of the two illustrated, with appropriate parallel connection to it of the switch leads 16 and 17.

In the preferred construction, assuming that the device is to be operated on approximately 14 volts, the high resistance heater is of approximately 80 ohms and the low resistance heater of approximately 3.0 to 6.0 ohms. Under these conditions a current of approximately .3 ampere flows through the circuit when the contacts 9 and 10 are separated, and the solenoids are adjusted so that they are capable of throwing the armatures 5 upon a current of approximately .85 ampere, but incapable of throwing the armatures if the current be approximately .3 ampere or thereabouts. These values are variable over substantial limits and they are provided in this specification solely to illustrate typical conditions.

The operation of the circuit is as follows:

When a given one of the push buttons 19 or 20 is depressed a current flows from the transformer through the push button to the solenoid with which it is in circuit and through the solenoid and the lead 23 to the thermocontroller. The solenoids are so connected that the depre-

sion of either push button effects the same control.

Current flowing through the lead 23 passes through the bimetallic strip 8, the high resistance heater 12, through the bimetallic strip 7 and through the low resistance heater 11 back to the transformer. At this time, the contacts 9 and 10 are separated from one another and the values of the resistances are such that the total resistance in the circuit may permit a current of approximately .3 ampere to flow, that is, a current insufficient to operate the selected solenoid.

While the high resistance and low resistance coils are heated in unison more energy is expended in the high resistance coil and, therefore, the bimetallic strip 8 is warped to a greater degree than the bimetallic strip 7, whereupon contact is made between the contacts 9 and 10.

With contact 10 being in engagement with contact 9, the high resistance coil 12 is shunted, the current flowing from the lead 23 through the bimetallic strip 8, the contacts 9 and 10 and the low resistance heater 11 back to the transformer. The current now increases to a magnitude sufficient to operate the solenoid 2 (for instance, .85 ampere) and, therefore, its armature is actuated to strike the bar 4 and sound the signal. Meanwhile, however, the current of greater magnitude is also flowing through the low resistance coil and it, in turn, is being heated substantially independently of the high resistance coil. Therefore the element 7 now warps away from the element 8 to break the engagement between contacts 9 and 10.

But as soon as the contact is broken the high resistance is restored in the circuit, the current drops and the high resistance coil is heated causing further relative movement of the bimetallic elements and causing consecutive contact of element 10 with element 9. While element 8 is short circuited it cools, and, conversely, when the element is being heated, element 7 is not being warped appreciably since the resistance of its heater is, comparatively, small. By virtue of these conditions the elements do not move beyond a field of movement determined by the relative equilibrium which is reached through the alternate heating and cooling of them.

In the circuit of Figure 3 the thermocontroller is the same as that shown in Figure 1 and the same reference numerals are applied to the various parts of the circuit. However, a resistor 25 is connected across the lead 24 and the bimetallic element 7 so as to be in parallel with the low resistance 11. This arrangement presents several advantages. If the current required for the operation of the solenoid is in the neighborhood of approximately .85 ampere, (and a current of this magnitude is usually required) it is necessary that the wire constituting the low resistance heater be of substantial size, otherwise too much heat is produced in the bimetallic element 7 and the frequency of operation tends to be altered.

As a practical matter, if the wire be sufficiently large to carry the current without undue heating, there is difficulty in wrapping the strip because of the stiffness of the wire. By the installation of a resistor 25 in shunt with the low resistance heating coil 11, the burdens imposed upon the latter are reduced and, therefore, the wire of this heater element may be of smaller size. The wire of smaller gauge does not stiffen the bimetallic element and, therefore, the bimetallic element 7 responds promptly when heat is

applied to it. As a typical illustration of the electrical conditions employed in the circuit of Figure 3, the resistor 25 may be approximately 14 ohms, the low resistance heater approximately 11 ohms and the high resistance heater the same as previously described.

The circuit of Figure 4 is similar to that of Figure 1 but is disclosed to show the utilization of a variable resistance for adjusting the periodicity to which the signal notes are sounded, so that the beat of the signals may be decreased or increased according to the desires of the user.

The circuit shown in Figure 4 comprises front and rear door solenoid striker units 26 and 27 which are connected, through the leads 28 and 29 to a lead 30 from the terminal 14. The leads 28 and 29 include, respectively, the front door and rear door push buttons 31 and 32. The remaining terminals of the solenoids 26 and 27 are connected respectively through leads 33 and 34, to a common lead 35 which includes a variable resistance indicated generally at 36. This resistance is attached through lead 37 to the bimetallic element 8, around which is wrapped the high resistance heater 12, as previously described. One of the terminals of the high resistance heater is attached to the bimetallic element 8 and the other to the bimetallic element 7, and a connection 38 is taken from the element 7 to the terminal 15.

The low resistance heater 11 is carried by the bi-metallic element 7, but one terminal of this heater is connected to the lead 29 and the other to the lead 28.

The variable resistance 36 is employed so that adjustments for different supply potentials may be made. For a given line potential, variation of the rheostat effects variation of the time intervals between successive notes. As a typical illustration of the electrical conditions which have been found satisfactory for this circuit, assuming that the solenoids would throw their armatures when supplied with current of approximately .85 ampere and will fail to operate at approximately .3 ampere, the low resistance heater may be of approximately 24 ohms, the high resistance heater may be as previously described, and the rheostat may be variable from approximately 1 to 7 ohms. As previously stated, these conditions are variable over substantially wide ranges and are provided to illustrate a typical embodiment for the benefit of those skilled in the art.

The operation of the circuit of Figure 4 is shown diagrammatically in Figures 5 and 6. As in Figure 5, when the front door button is depressed the low resistance heater 11 is connected in series with the solenoid winding 27 and these two elements in turn are connected in parallel with the winding of the solenoid 26 which operates to sound the front door signal.

As illustrated in Figure 6, when the push button 32 at the rear door is operated, the low resistance element 11 is connected in series with the winding of the solenoid 26, and these in turn are connected in parallel with the winding of the solenoid 27 which operates the rear door signal.

The push button, shown in the circuit of Figure 7, is capable of holding the circuit to the chime for a predetermined interval of time when the push button is depressed. Leads 39 and 40 with which this push button is provided are connected in the circuit in the usual manner in sub-

stitution for the push buttons shown in the circuits of Figures 1, 3 and 4.

The holding apparatus comprises a bimetallic element 41 carrying a heating coil 42, one terminal of which is in connection with the lead 40 and the other with the bimetallic element. The element 41 is provided with a latch 43 and is resiliently mounted at the end opposite the latch, as upon a flexible member 44. A latch 45 carried on a shank 46 of the push button 47 is arranged to engage the latch 43 when the push button is depressed. The push button itself slides through a collar 48 which is in electrical connection with the lead 39 and the collar in turn is carried in an insulating housing 49 which may be mounted to a door frame in the usual manner. The shank 46 carries a washer 50 within the housing for engagement with a compression spring 51.

The latch 45 is configured to move past the latch 43 and then be caught by it when the push button is depressed. An electrical connection is made through the lead 39, the collar 48, the shank of the device and the latch 43, through the heating coil 42 and the lead 40. When current flows the heating coil 42 warps the element 41 causing it to drag the latch 45 and permit the push button to be released under the influence of the spring 51. The interval of time required is dependent upon the extent of engagement of the latches and the intensity of the heat generated in the coil 42. In a typical apparatus the push button, once depressed, may be released after approximately 6 or 8 seconds, during which time the push button completes the circuit to the chime apparatus so that a succession of signals is sounded automatically.

The thermocontroller element shown in Figure 8 is of a modified form and comprises a strip portion 52 and a strip portion 53 which are welded or connected at adjacent endwise portions to form a substantially continuous strip element. Portion 53 carries a contact 54 which cooperates with a contact 55. These contacts function in the same manner as the contacts 9 and 10 as shown in Figures 1 and 2.

The portion 52, at the end opposite the contact 54, is supported in a suitable pillar or mounting member 56 and the portions 52 and 53 are so connected that they warp in opposite directions when they are heated, that is, the extremity of the portion 52 moving in the direction of the upper arrow and the portion 53 moving in the direction of the lower arrow, as shown.

The portion 52 carries the high resistance heater 12 and the portion 53 the low resistance heater 11. The electrical connections to these heater elements may be as described in connection with Figure 1 or exactly the same as those shown in Figure 2 and, therefore, further description is unnecessary.

When the heater coil 12 is energized the bimetallic element 52 is warped upwardly and carries contact 54 into engagement with contact 55. Conversely, when the contact is made and heater 12 is shunted, the heater element 11 of 53 warps the latter element downwardly to open the contact.

It will be noted from the foregoing description of all of the circuits that the arrangements provide several important advantages. The thermocontrollers are self-compensating. Variations in the temperatures of the atmospheres 75 surrounding them will not change their mode or

frequency of operation. Sparking at the contacts through which resistance is shunted is greatly reduced since the current through the contacts is not cut off completely when the contacts are opened, but only changes from a relatively high value to a relatively low value. Moreover, there is no difficulty in the making of contact whether the tension be relatively strong or relatively weak.

Having described my invention, I claim:

1. A circuit interrupter comprising a high resistance thermoresponsive element and a low resistance thermoresponsive element having portions free to move relatively in the same direction, the said resistances of said thermoresponsive elements being interconnected whereby, when energized in unison the high resistance thermoelement approaches the low resistance element and the low resistance element relatively recedes from the high resistance element when the latter is shunted and means for shunting the high resistance heater comprising contacts closed when the thermoresponsive elements are in predetermined relative positions, whereby the high resistance and the low resistance heaters alternately cause said contacts to open and close.

2. An electrical circuit interrupter comprising

ing a high resistance, a low resistance, bimetallic elements respectively physically associated with the high resistance and the low resistance so as to be heated respectively by the high resistance and the low resistance, and contact making means, controlled by said bimetallic elements, adapted to shunt the high resistance from the circuit when the high resistance has caused one of the bimetallic elements to warp to a predetermined degree.

3. An interrupter device comprising a pair of thermalresponsive elements, mutual cooperable contact members operated by said thermalresponsive elements, electrical resistance heaters arranged adjacent said thermalresponsive elements respectively for heating them, one of said resistances being arranged to exert a greater heating effect upon its thermalresponsive element than the other, the said thermal elements being arranged to warp in the same direction when they are heated, the said contacts being arranged to shunt one of the resistances when they are in engagement with one another, whereby the unshunted resistance exerts a heating effect upon its thermalresponsive element to move the contacts out of engagement with one another.

LOWELL M. ALEXANDER.
